UNITED STATES PATENT OFFICE

148,291

DESIGN FOR A GLOCKENSPIEL

Robert Emanuel, Brooklyn, N. Y., assignor to William Jay Emanuel Co., New York, N. Y., a partnership consisting of Benjamin F. Jay,
Robert Emanuel, and William J. Emanuel

Application July 27, 1946, Serial No. 132,025

Term of patent 3½ years

(Cl. D56—1)

To all whom it may concern:

Be it known that I, Robert Emanuel, a citizen of the United States, residing in Brooklyn, county of Kings, State of New York, have invented a new, original, and ornamental Design for Glockenspiel, of which the following is a specification, reference being had to the accompanying drawings, forming a part thereof, in which:

Fig. 1 is a front elevational view of my new design of glockenspiel, and

Fig. 2 is a side elevational view thereof.

I claim:

The ornamental design for a glockenspiel, as shown.

ROBERT EMANUEL.
